UNITED STATES PATENT OFFICE.

PERRY H. HAMILTON, OF MOUNT WASHINGTON, MARYLAND, ASSIGNOR TO THE P & M COMPANY, OF CHICAGO, ILLINOIS, A CORPORATION OF ILLINOIS.

RAIL ANCHOR.

Application filed July 19, 1924. Serial No. 726,995.

To all whom it may concern:

Be it known that I, PERRY H. HAMILTON, a citizen of the United States, residing at Mount Washington, in the State of Maryland, have invented certain new and useful Improvements in Rail Anchors, of which the following is a specification.

My invention relates to rail anchors of the type comprising a clip adapted to be applied to the base flange of a rail from one side thereof, and when in position adapted by engagement with some fixed portion of the track to hold the rail from creeping longitudinally.

It is the object of my invention to provide a new and improved combination of parts by which such a clip can be utilized to advantage for the purpose specified, and also to provide an improved form of clip.

The preferred means by which I have accomplished my several objects are illustrated in the drawing and are hereinafter specifically described. That which I believe to be new and desire to cover by Letters Patent is set forth in the claims.

In the drawing,—

Fig. 1 is a transverse sectional view through a rail, partly broken away, being substantially a section taken on line 1—1 of Fig. 2.

Fig. 2 is a top plan view of the parts shown in Fig. 1.

Referring to the drawing,—10 indicates a rail, supported by a cross tie 11, with a tie plate 12 interposed between the tie and the rail. Mounted on the flange of the rail at one side thereof, there is a clip 13, preferably formed of high-grade steel, with its end portions normally spaced apart a distance less than the thickness of the rail base at the points engaged by said end portions, whereby said end portions are spread apart when the clip is driven into position upon the flange. The clip 13 is made of a bar of such cross-sectional size, and the shape and dimensions of the clip are such that when the clip is driven into operative position, as shown in Fig. 1, the clip has a very strong spring grip on the rail so as to prevent movement of the clip longitudinally of the rail.

In the construction illustrated, the tie plate is utilized for holding the clip against movement with respect to the cross tie longitudinally of the track, and also for holding the clip against backing transversely from

the flange of the rail. As is best shown in Fig. 1, the tie plate is provided with a slot 14 extending transversely of the rail and of such dimensions and so positioned that the outer face 15 of the slot engages the outer face of the clip, serving to hold the clip in position. The tie plate 12 is preferably provided with a rib or shoulder 16 adapted to engage the side face of the flange of the rail at the opposite side. The clip is thus effectively held against withdrawal from the flange. At the same time the clip is held against movement with respect to the tie longitudinally of the track by reason of the engagement of the clip with the side faces of the slot 14, the plate itself being, of course, held in position with respect to the cross tie by means of spikes 17, or in any other suitable manner.

In its application to a rail, the anchor member comprising the clip 13 is preferably first applied to the rail by driving it into position upon the flange with the plate 12 removed. After the clip has assumed its operative position, the plate 12 is then slipped between the rail and the cross tie, it being necessary, of course, that the rail and tie be separated sufficiently for providing clearance for the plate below the clip until the plate can be brought into position for permitting the clip to enter the slot 14. The rail and cross tie are then permitted to assume their normal distance apart with the rail supported from the tie by the plate 12, in which position the clip is held against removal.

While I prefer to employ the construction as illustrated in the drawing, in which the longitudinally extending face or shoulder by which the clip is held in position is provided in the form of the outer face of a slot in a tie plate, it will be understood that I do not desire to limit myself to this particular construction except so far as the same is specifically covered by the claims, since it is evident that changes may well be made in the detailed form of the device without departing from the spirit of my invention.

I claim:

1. A rail anchor comprising a clip formed from a metal bar bent upon itself to provide spaced portions adapted to be driven into gripping engagement with the upper and lower surfaces of the base flange of a rail at one side of the rail, and a plate interposed

between the rail and the cross tie and provided with a slot extending transversely of the rail for the reception of the lower end portion of the clip, the arrangement being such that the clip has a substantially snug fit in the slot longitudinally of the rail and that the outer face of the slot is adapted by engagement with the outer face of the clip to hold the clip in its operative gripping position on said flange.

2. A rail anchor comprising a clip formed from a metal bar bent upon itself to provide spaced end portions having flat bearing surfaces adapted to be driven into gripping engagement with the upper and lower surfaces of the base flange of a rail at one side of the rail, and a plate interposed between the rail and the cross tie and provided with a slot extending transversely of the rail for the reception of the lower end portion of the clip, the arrangement being such that the outer end of the slot engages the outer face

of the clip to hold the clip in its operative position on the flange.

3. A rail anchor comprising a clip formed from a metal bar bent upon itself to provide portions which embrace the upper and lower surfaces of a rail base at one side thereof and adapted to be driven into resilient gripping engagement with said surfaces and into engagement with the longitudinal edge of said base, and a plate interposed between the rail and the cross tie and provided with a slot extending transversely of the rail for the reception of the lower end of the clip, the arrangement being such that the clip bears against the side faces of said slot so as to be held in a position substantially at right angles to the length of the rail, and such that the outer end face of the slot is adapted by engagement with the outer face of the clip to hold the clip in its operative gripping position on the flange.

PERRY H. HAMILTON.
